REGISTERING SYSTEM

Philip H. Burn, New York, N. Y.

Application December 29, 1951, Serial No. 264,105

11 Claims. (Cl. 235—92)

1

This invention relates to registering devices and more particularly to systems for operating indicating means in response to sensing means.

An object of the invention is to provide circuit means whereby indicating means may be operated in an ascending or descending order in accordance with the order in which a plurality of sensing means are actuated.

Another object of the invention is to provide circuit means whereby indicating means responsive to the actuation of a plurality of sensing means will be responsive only upon actuation of the sensing means in proper sequence.

A further object of the invention is to provide circuit means for the operation of indicating means in response to sequential actuation of sensing means in which the response of said indicating means will occur only after completion of a predetermined sequence of actuations of said sensing means.

Still another object of the invention is to provide circuit means for the operation of indicating means in an ascending and descending order only upon actuation of a plurality of sensing means in a predetermined sequence and only upon completion of said sequence of actuations.

While the present invention has wide application in a number of systems, it is particularly useful in counting devices of the type disclosed in my copending application Serial No. 35,350, filed June 26, 1948, now Patent No. 2,644,150, of which this application is a continuation-in-part.

Fig. 1 is a schematic wiring diagram of one form of circuit embodying the principles of this invention; Fig. 2 is a schematic wiring diagram of a modified type of circuit; and Fig. 3 is a plan view of a typical installation of devices using the present invention for counting the passage of vehicles moving along a traffic lane.

Broadly speaking the present invention contemplates the employment of a plurality of sensing means, such as photo-electric cells, or physically-operated relays, or other well-known devices, which are disposed in predetermined relationship to each other in such a manner that they will respond in sequence to the conditions which it is desired to observe. The sensing means, by virtue of opening or closing certain portions of the circuit to which they are connected, are enabled to operate indicating means in such a manner that indications occur only in response to full and complete actuation of the sensing means in their proper sequence.

In Fig. 1 there is shown an arrangement in accordance with the disclosure of my copending

2

application Serial No. 35,350, of a system for counting vehicles as they enter or leave a parking area, the purpose of the system being to provide at all times an accurate count of the number of vehicles present within the area.

This system includes a twin-beam photo-cell system employing a first electric lamp 60 constantly casting a beam across the entrance way of the parking area to a first photoelectric cell 61; and, as long as this beam is uninterrupted, it will be understood that a relay 62 may be operative to maintain its contacts open. Upon interruption of the beam between lamp 60 and photocell 61, relay 62 will be deenergized so that its armature may drop to complete a circuit. In like manner, a second lamp 64 may be disposed to cast a continuous beam across the entrance-exit way to the parking area and upon a second photocell 65; and, as long as this second beam is uninterrupted, a relay 66 may remain energized so as to keep its contacts open. The spacing between the two beams is preferably great enough so as not to be simultaneously interrupted by an object which it is not desired to count, such as a person or a small group of persons, but this spacing should of course not exceed the minimum length of the object which it is desired to count, such as a vehicle entering or leaving the parking area. It is thus expected that simultaneous operation of both beams will be necessary before a counting impulse may be derived, and the order of interruption of the beams may determine whether such counting impulses register the entrance or exit of a vehicle. In the form shown, the two types of counting impulses are available for the operation of an indicating means, which for example only is denoted by a differential counting mechanism 23, of conventional design, actuated by the operation of one or the other of solenoids 19—21 and their associated index-ratching mechanisms.

The circuits utilizing the photocell operated solenoids 62—66 may be so interlocked as to prevent the unnecessary registration of a count should a vehicle inadvertently interrupt one beam, only to back out and fail to interrupt the other beam. Also, the circuits may provide a means for failing to register a count should both the beams be interrupted by a vehicle only to have the vehicle back out. In other words, I prefer that the circuits associated with the relays 62—66 be so arranged that the in-count or out-count be derived only after a vehicle has interrupted a first beam, has then interrupted a second beam, and has passed both beams to the

point of permitting re-establishment of the second beam.

Each of the relays 62—66 may be interlockingly associated with an interlocking relay 67—68, respectively. The relays 67—68 are each shown to include normally closed contacts 67'—68' and normally open contacts 67''—68''. The contacts 67''—68'' are preferably of a type to make contact only during the movement of the contacts 67'—68'', that is, the contacts 67''—68'' in the form shown may only close for an intermediate and transiently occupied position, and these contacts are not closed during the steady-state condition of an energized or of a deenergized relay 67—68, as the case may be. As a further feature, holding coils 69—70 may be associated with the relays 67—68. When energized, holding coils 69—70 may be sufficiently strong to hold the relay contacts in operated position, but the holding coils 69—70 are of themselves preferably insufficiently strong to raise or to operate the contacts of relays 67—68. To complete the circuits for relays 62—66, there may be a further normally open relay 71 to be operated directly by the relay 62, and there may be another further normally open relay 72 to be operated directly by the relay 66. The contacts of the normally open relays 71 may be in series relation with the ratchet solenoid 21 and with the transiently wiping contact 69'', and in like manner the contacts of normally open relay 72 may be in series with the ratchet solenoid 19 and with the transiently wiping contacts 67''. For a purpose which will be clear, the nature of relays 71—72 is preferably such that their contacts break relatively slowly or even with a slight delay, as compared with the break or drop-out action of relays 69—70.

In operation, let it be assumed that a vehicle is passing the two light beams from right to left in the sense of Fig. 1. The beam between lamp 60 and photocell 61 will then be the first to be interrupted, and upon such interruption relay 62 will be deenergized to close its contacts and thus simultaneously to close the contacts of relays 71, to energize the holding coil 70 for relay 68, to open the normally closed contacts 67' of relay 67, and to cause contacts 67'' transiently to wipe while raising the armature of contacts 67'' to an upper (dotted) position. This wiping action will be understood to have produced no function, inasmuch as the circuit of contacts 67'' will at the time have been open at the relay 72. Should the vehicle be backed up without breaking the beam of lamp 64, it will be understood that all relays will have been returned automatically to the positions shown, without registering or deriving a counting impulse or function.

As a next step in the operation of the counting device of Fig. 1, the beam of lamp 64 will be interrupted while the beam of the lamp 60 remains interrupted. When both beams thus become interrupted, relay 66 will be deenergized so as simultaneously to close the contacts of relay 72 and to energize the holding coil 69 of relay 67; relay 68 will not be operated at this time, inasmuch as the circuit therefor will have been open at the contacts 67'. Here again, it will be noted that if the vehicle should be backed so as to reestablish both beams, all relays may return to the positions shown in Fig. 1 without registering a counting impulse.

As a third step in the operation, the rear end of the vehicle will pass the beam of lamp 60 so that this beam may again impinge upon pho-

tocell 61. Relay 62 may then be re-energized, but it will be noted that the holding coil 69 may still be operative to retain contacts 67' and 67'' in their raised positions. This operation of relay 62 will be understood to have the further functions of deenergizing the holding coil 70 of relay 68, and of opening the contacts of relay 71. Again it will be noted that should the vehicle be backed away from the counter at this third step in the operation thereof, no counting impulse will be derived.

The fourth and final step in the operation of my counter may occur when the vehicle completely passes the second light beam, so as to reactivate photocell 65 and thus to energize relay 68. This operation may result in an immediate deenergization of the holding coil 69 so that, as the contacts 67'' drop and brush, there may be a circuit completed to the counting or ratcheting solenoid 19. At the same time, energy to relay 72 will have been cut off but, due to the above-mentioned slow-action or delay features which may be incorporated in the relay 72, the contacts of relay 72 are preferably not opened until after the contacts 67'' of relay 67 have brushed to produce the described counting function.

By virtue of the complete electric symmetry of connections to the relays operated by both photocell circuits, it will be understood that a reverse order of interrupting the light beams may transiently complete a circuit through contacts 68'' and the contacts of relay 71 so as to produce a ratcheting or counting impulse for operation of solenoid 21. This reverse order of light-beam interruption may occur for a vehicle leaving the monitored parking area, and the generated impulse will be understood to produce an out-counting operation of solenoid 21.

The modified form of circuit, shown in Fig. 2, includes additional means for insuring accuracy in the actuation of the indicating means 23 and for preventing its false operation under circumstances whereby the photocells 61 and 65 may accidentally have the light from the sources 60 and 64 cut off sequentially but in which case it is not desired to secure an indication. In the use of the circuit as a vehicle counter it is possible that two pedestrians might pass in front of the light sources 60 and 64 in such a time sequence that their combined actions would be the equivalent of the cutting off of the light by a passing vehicle.

In order to prevent such false indications, a third sensing means may be employed, in the form of a floor switch 75, which may be placed in the path of the vehicle, as shown in Fig. 3, at some position between the light source 60 and its photocell 61, and light source 64 and its photocell 65. In certain applications of this registering device it would also be possible to substitute some other form of sensing device for the floor switch, or it might be desirable to use a third light source and photocell for this purpose.

In addition, the two principal sensing means which in the previously described embodiment included photocells 61 and 65 are provided with relays 77 and 78, respectively, to be operated in response to cutting off of the light from sources 60 and 64 in the same way as in the case of the previously described relays 62 and 66. However, the relays of the present modification differ from the former in that they are each two normally open contacts instead of a single one.

The additional sensing means, such as the floor switch 75, is arranged in any well known manner

to close a circuit between a relay 76 and the main power supply whenever this sensing means is responsive to an object to be registered by the other sensing means. It is to be noted that, whereas the single contact of relays 62 and 66 of the previously described circuit are always connected to one side of the main power supply, the contacts 79-80, and 81-82 of relays 77 and 78 of the present modification are connected to this one side of the power supply only through the medium of a subsidiary circuit which includes relay 76.

In other respects, however, the closing of contact 79 establishes a condition in the circuit which is equivalent to the closing of the contact of relay 62 in the previous modification. The same thing is true of contact 81 as compared to previously described relay 66, except that in each case in the circuit of Fig. 2 the energization of those portions of the circuit which are controlled by contacts 79 and 81 will be dependent upon the closing of relay 76 which connects the contacts to the power supply.

As previously indicated, relay 76 is initially energized by the closing of the switch 75. If, in addition either one or both of the relays 77 and 78 have been energized by the operation of their associated photocells 61 and 65, a circuit parallel to that established by switch 75 will be formed by virtue of the closing of either or both of contacts 80 and 82. Under this condition, as long as one or both of the beams of light falling upon photocells 61 and 65 is interrupted, and one or both of contacts 80 and 82 are closed, the relay 76 will remain energized even if switch 75 should be subsequently opened. However, once the circuit established by contacts 80 and 82 is broken while switch 75 is open, relay 76 will not again become energized solely by closure of one or both of contacts 80 and 82 because these contacts can only connect with the power supply through the contact which is closed by relay 76 when it is first energized by closure of switch 75.

In operation of the modified circuit of Fig. 2, let it again be assumed that a vehicle is passing the two light beams from right to left in the sense of Fig. 2. As before, when the beam between lamp 60 and photocell 61 is interrupted its associated relay 77 will be deenergized and its contacts 79 and 80 will be closed. But at this point none of the other circuits will be affected until the vehicle passes over the floor switch 75, causing relay 76 to be energized to close the circuit between the main power supply and contacts 79 and 80. At this point holding coil 70 will be energized, contact 67' will be opened, and contacts 67'' will be transiently connected as the armature is raised to its upper (dotted) position. The operation of these latter elements is similar to their operation during the first step as described in connection with the circuit of Fig. 1, and no indicating function will be produced. Similarly, if the vehicle should then back up to a point to the right of lamp 60 all relays would return to their original positions. If the vehicle were to pass just to the left of the floor switch, or back up to some point between the floor switch and lamp 60, the relays would remain in the positions just described because of the fact that when contact 80 was closed by the deenergization of relay 77 the circuit was established which maintains relay 76 energized and thus connects contact 79 with the power supply.

If the vehicle passes far enough to the left, the light from lamp 64 will be interrupted in addi-

tion to the light from lamp 60. Relay 78 will then be deenergized, causing contacts 81 and 82 to close. The closing of contact 82 will have no effect, inasmuch as its circuit is already closed by contact 80. The closing of contact 81 will simultaneously energize holding coil 69 and close the contacts of relay 72; relay 68 will not be operated at this time, inasmuch as the circuit therefor will have been open at the contacts 67'. As before, if the vehicle should be backed so as to reestablish both beams of light, all relays may return to their original positions without performing any registering function.

As the vehicle passes further to the left the beam from lamp 60 will again impinge on photocell 61 to energize relay 77. While this will cause the deenergization of relay 67, the contacts 67' and 67'' will remain in their upper position under the influence of holding coil 69, while holding coil 70, and relay 71 will be deenergized. Furthermore, it should be noted that the opening of contact 80, when relay 77 is energized, will have no effect because contact 82 will be closed so as to maintain the circuit established by relay 76; this will also be true even if the rear wheels of the vehicle have passed to a point between the floor switch and lamp 64. As in the previous instances, if the vehicle should back up completely to the right of lamp 60 no indicating function would have been performed by the circuit.

When the vehicle has passed completely to the left of lamp 64, relay 78 will again be energized to open contacts 81 and 82, thus deenergizing holding coil 69, and permitting contacts 67' and 67'' to drop. The downward movement of contact 67'' will create a transient connection between the contact of relay 72 and the solenoid 19, and while the relay 72 has been simultaneously deenergized at the same time, due to the delayed action of its contacts they will not open until the solenoid has been actuated sufficiently to indicate the passage of the vehicle.

As in the case of the circuit of Fig. 1, movement of a vehicle in a direction from left to right so as to interrupt the light beams in the reverse order will cause a transient circuit to be completed through contacts 68'' and the contacts of relay 71 to energize solenoid 21 for performing another indicating function.

It will be appreciated, therefore, that the present invention is not limited for use in counting vehicles but is applicable to a variety of situations wherein it may be desired to provide registering or indicating functions in response to the presence of a plurality of objects.

While the invention has been described in detail in a preferred form only, it will be understood that modifications may be made within the scope of the appended claims.

I claim:

1. In a counting system of the character indicated, two spaced counting elements to be traversed, the spacing between said elements being less than the expected length of an object to be counted, first indicating means responsive to a first sequential traversal of both said elements and operative only upon travel past the second traversed of said elements, and second indicating means responsive to traversal of both said elements in the opposite sequential order and operative only upon travel past the then second traversed of said elements, whereby there may only be operation of either of said means upon a complete traversal of said elements in either of 75 said directions.

2. A counting system according to claim 1, in which each of said spaced counting elements includes a lamp casting a beam of light for impingement upon a photoelectric cell.

3. In a counting system of the character indicated, two spaced counting elements to be traversed, the spacing between said elements being less than the expected length of an object to be counted, first relay means operated by one of said elements, and second relay means operated by the other of said elements, a first circuit to be partially completed upon operation of said first relay for completion upon operation of said second relay, and a second circuit to be partially completed upon operation of said second relay for completion upon operation of said first relay, for the purpose described.

4. In a registering system of the character indicated having a pair of spaced sensing means to be sequentially responsive to an object including, relay means for each of said sensing means, circuit means whereby each of said relay means may be energized when the respective sensing means is so responsive to an object, each of said relay means being normally connected to complete a portion of said circuit means to permit energization of the other relay means and to break said portion of the circuit when energized, holding means for each of the relay means actuated when the other sensing means is so responsive to prevent reestablishment of said normal condition while the other sensing means is so responsive, each of said relay means also having switching means to establish a respective circuit for registering means when released by the respective holding means, and delayed-action means to allow completion of the registering circuit, whereby respective circuits for registering means will be completed only on complete traversal of the sensing means by an object moving in the respective direction.

5. A system of the character defined in claim 4, having secondary sensing means disposed between said first-mentioned sensing means connected in the energizing circuit for said relay means to initially complete said circuit only when the secondary sensing means is responsive to an object to be registered, and energizing means for the secondary sensing means connected in said circuit whereby said completed circuit for energizing the relay means may be thus maintained so long as a first-mentioned sensing means is responsive to an object.

6. In a registering system of the character indicated having a pair of spaced sensing means to be sequentially responsive to an object including, primary relay means and secondary delayed-action relay means for each of said sensing means, circuit means whereby the respective primary and secondary relay means may be energized when the respective sensing means is so responsive to an object, each of said primary relay means being normally connected to complete a portion of said circuit means to permit energization of the other of said primary relay means and to break said portion of the circuit when energized, holding means for each of the primary relay means actuated when the other sensing means is so responsive to prevent reestablishment of said normal condition while the other sensing means is so responsive, each of said primary relay means also having switching means connected in series with the secondary relay means of the other sensing means, whereby a respective transitory circuit for registering means

is completed only when the primary and secondary relay means of both sensing means have been sequentially energized and deenergized by complete traversal of said sensing means by an object moving in the respective direction.

7. A system of the character defined in claim 6, having secondary sensing means disposed between said first-mentioned sensing means connected in the energizing circuit for said relay means to initially complete said circuit only when the secondary sensing means is responsive to an object to be registered, and energizing means for the secondary sensing means connected in said circuit whereby said completed circuit for energizing the relay means may be thus maintained so long as a first-mentioned sensing means is responsive to an object.

8. In a system of the character indicated having sensing means responsive to the movement of an object in a plurality of directions to register said movements, circuit means for said sensing means to actuate indicating means in accordance with the responsiveness of the sensing means, secondary sensing means arranged to be responsive to the presence of the object to be indicated, and energizing circuit means for said first circuit means, said secondary sensing means being connected to said energizing circuit means to energize the first circuit means only when the secondary sensing means is so responsive and to maintain the first circuit means energized thereafter so long as the first-mentioned sensing means is so responsive.

9. In a system of the character indicated having sensing means responsive to the movement of an object in a plurality of directions to register said movements, a plurality of circuit connections for the sensing means to actuate indicating means in accordance with the responsiveness of the sensing means, secondary sensing means arranged to be responsive to the presence of the object to be indicated, energizing circuit means for the first-mentioned plurality of circuit connections, and relay means actuated by responsiveness of the secondary sensing means connected with said energizing circuit means to energize the first-mentioned plurality of circuit connections only when the secondary sensing means is so responsive and to maintain the first-mentioned plurality of circuit connections energized thereafter so long as the first-mentioned sensing means is so responsive.

10. In a system of the character indicated having sensing means responsive to the movement of an object in a plurality of directions to register said movements, a plurality of circuit connections for the sensing means to actuate indicating means in accordance with the responsiveness of the sensing means, said circuit connections including relay means to complete a circuit to be energized, secondary sensing means disposed to be responsive to the presence of the object to be indicated, and energizing circuit means including relay means actuated by responsiveness of the secondary sensing means to energize the first-mentioned circuit connections only when the secondary sensing means is so responsive and to maintain the first-mentioned sensing means is so responsive.

11. In a system of the character indicated having a pair of spaced sensing means to be sequentially responsive to traversal of an object in opposite directions, circuit means for said sensing means to actuate means to register said movement in each direction only after traversal

of both said sensing means in a single direction by the object, secondary sensing means disposed between said first-mentioned sensing means to be responsive to the object during said movement, energizing circuit means for the first-mentioned circuit means, and relay means actuated by responsiveness of the secondary sensing means connected with said energizing circuit means to energize the first-mentioned circuit means only when the secondary sensing means is so responsive and to maintain the first-men-

tioned circuit means energized thereafter so long as one of the first-mentioned sensing means is so responsive.
